US00D540775S

(12) **United States Design Patent** (10) Patent No.: **US D540,775 S**
(45) Date of Patent: **** Apr. 17, 2007**

(54) **PORTABLE CD PLAYER WITH RADIO**

(75) Inventor: **Yong De Zhang**, Dong Xing (CN)

(73) Assignee: **Coby Electronics Corporation**,
Maspeth, NY (US)

(**) Term: **14 Years**

(21) Appl. No.: **29/233,909**

(22) Filed: **Jul. 12, 2005**

(51) **LOC (8) Cl. 14-01**

(52) **U.S. Cl. D14/168**

(58) **Field of Classification Search** D14/160-165,
D14/167-168, 172, 193-198, 188; 360/99.02,

360/99.07; 369/75.11, 75.21, 77.21, 77.11;
720/612, 619, 647, 655; 455/344, 347-351

See application file for complete search history.
